MISSILE LAUNCHING SYSTEM

Lawrence J. Reeves, Palo Alto, Calif., assignor, by mesne assignments, to the United States of America as represented by the Secretary of the Navy

Filed Jan. 8, 1962, Ser. No. 165,049

32 Claims. (Cl. 89—1.7)

This invention relates to a system for preventing the launching of a missile at an unsafe angle, and more particularly to a system capable of indicating the coincidence of safe missile firing conditions and preventing firing when dangerous missile fallback conditions exist.

In recent years, vertically launched missiles have come to play a vital role in national defense. Such missiles may be launched from land, surface ships, or submarines during combat or test exercises. In the course of developing vertically launched missiles a need has arisen to insure prevention of firing whenever conditions exist which would allow a dud missile or "dummy" test vehicle to fall back on the launcher. It is, therefore, desirable to allow the initiation of missile or test vehicle firing only when such a launching would propel the missile fired a sufficient lateral distance from the launcher. Thereby, the possibility of a collision between the launcher and the missile, should fallback occur, would be eliminated.

The present invention utilizes an electronic-electro-mechanical computing-indicating system for instructing the missile launching officer when it is safe to fire and for preventing completion of the firing circuit when it is unsafe to fire. To avoid fallback the launcher may be listed to a safe angle. In the instant invention, when static lists are imposed, the angle of list or heel actuates a servo loop in the Safe Launch Angle Gate System, hereinafter entitled SLAG system. The actuated servo loop then operates indicators, and relays and switches for safety interlocks in the missile launcher firing mechanism. To allow for the dynamic condition of roll velocity SLAG utilizes an analog angle computer which operates to indicate the percentage of "GO" or safe firing time existing at any given time as well as instantaneous roll angle. These indications have a fixed time delay to allow sufficient time for missile launch initiation and for the missile to clear the launcher muzzle. Thus, the computer predicts the angle, with respect to the vertical, of the launcher at the time the missile will clear the launcher. Of course, the computer may also act to condition a relay system to complete or interrupt a firing circuit.

Accordingly, an object of the present invention is the provision of a system for indicating the existence of safe firing conditions and preventing firing when dangerous missile fallback conditions exist.

Another object is to provide a system for allowing initiation of missile firing only when conditions exist thereby indicating that a missile fired would be propelled a sufficient lateral distance from the launcher to eliminate the possibility of a collision between the launcher and the missile should fallback occur.

A further object of the invention is the provision of a system which actuates relays and switches for safety interlocks in a missile launcher firing system when the launcher is listed to a satisfactory angle to thereby eliminate the hazard of missile fallback on the launcher.

Still another object is to provide a system for indicating static list conditions and future dynamic roll conditions and for respectively allowing and preventing completion of a missile firing circuit for missile launching during safe and hazardous periods of time.

Yet another object of the present invention is the provision of dual systems for alternate or simultaneous operation which indicate static and dynamic conditions of a

2

missile launcher and prevent the initiation of missile launching where the static orientation of the launcher provides hazardous fallback conditions or where the dynamic roll velocity conditions of the launcher are such as to provide hazardous fallback conditions when the missile clears the launcher muzzle.

Other objects and many of the attendant advantages of this invention will be readily appreciated as the same becomes better understood by reference to the following detailed description when considered in connection with the accompanying drawings wherein:

FIG. 1 is a rear view illustrating a missile launching ship's physical and mathematical orientation.

FIG. 2 is a partial top view of FIG. 1 further illustrating a missile launching ship's physical and mathematical orientation.

FIGS. 3A, 3B, 3C, and 3D are portions of a schematic diagram for the SLAG system.

FIG. 4 is an illustration depicting the interrelationship of FIGS. 3A, 3B, 3C, and 3D when connected to form the SLAG system.

FIG. 5 is a schematic diagram of an alternate embodiment of a portion of the SLAG system.

FIGS. 6A and 6B are, respectively, left and right portions of a block diagram of the SLAG analog angle computer.

Where missiles are launched in a substantially vertical manner from a launcher the requirement exists that the launcher be at such an angle of static list or dynamic roll that the danger of fallback damage to the launcher is prevented. The safe launch angle, of course, is determined by the physical launcher location on the platform or vessel and the method of missile launch.

The fallback analysis embodied in the instant invention and presented herein is two-fold; one being for a static angle of list and one being for a dynamic roll-rate angle. It should be understood that the mathematical equations hereinafter set forth are general and may be modified to fit a variation of launching parameters and criteria. It should be further understood that the assumptions are made that roll motion is sinusoidal, and that muzzle velocity and gravity are constant. It is further assumed that the launcher or ship maintains generally constant vertical motions and that there are no violent motions of the ship after launch. Reference to the mathematical and physical orientations of the launching ship as illustrated in FIGS. 1 and 2 will be helpful in the following mathematical considerations of fallback analysis.

Initial missile motions are:

$$\dot{Y}_{m0} = V_m \cos \theta_0 + (e \sin \theta_0 + b \cos \theta_0) \theta_0 + (d \cos \sigma_0 - e \sin \sigma_0) \dot{\sigma}_0 + \dot{h}_0 \quad (1)$$

and

$$\dot{X}_{m0} = V_m \sin \theta_0 + (e \cos \theta_0 - b \sin \theta_0) \theta_0 + (d \cos \delta_0 - b \cos \delta_0) \dot{\delta}_0 + \dot{S}_0 \quad (2)$$

where,

Y = distance missile travels above launch point (LP)

$\dot{Y}$ = vertical velocity

$\dot{X}_{m0}$ = initial vertical velocity of missile (with respect to ship)

X = miss distance (perpendicular to ship's longitudinal centerline (C))

$\dot{X}$ = horizontal velocity

X_{m0} = initial vertical velocity of missile (with respect to ship)

e = height of LP above ship's center of rotation (C_m)

b = LP distance from ship's longitudinal centerline (C)

d = distance fore from ship's transverse centerline (C)

h = heave

$\dot{h}$ = heave rate

s =sway
 $\dot{s}$ =sway rate
 V_m =muzzle velocity of missile
 θ =roll angle
 $\dot{\theta}$ =roll rate (angular velocity)
 σ =pitch
 $\dot{\sigma}$ =pitch rate (angular velocity)
 δ =yaw
 $\dot{\delta}$ =yaw rate

All sub 0's indicate initial conditions; applicable equations for motion are:

$$X = X_0 + Xt \quad (3)$$

and

$$Y = Y_0 + \dot{Y}t + \frac{1}{2}at^2 \quad (4)$$

where t =time.

Where the ship's motion is constant

$$Y_0 + \dot{Y}s_0 t = Y_0 + \dot{Y}_{m_0} t + \frac{1}{2}gt^2 \quad (5)$$

$$\dot{Y}_{m_0} = \dot{Y}_{s_0} + V_m \cos \theta_0 \quad (6)$$

$$V_m \cos \theta_0 t f + \frac{1}{2}gt^2 = 0 \quad (7)$$

and

$$t f = \frac{2V_m \cos \theta_0}{-g} \quad (8)$$

where:

$\dot{Y}_{s_0}$ =initial vertical velocity of ship

g =gravity (32.2 ft./sec./sec./

$t f$ =time of flight

missile travel is:

$$(X - X_0) = t f \dot{X}_{m_0} = \text{range from ship} \quad (9)$$

where ship's motion is not constant missile travel is:

$$(X - X_0) = \left(\frac{2V_m \cos \theta_0}{-g} \right) (V_m \sin \theta_0 + \dot{X}_{s_0}) \quad (10)$$

where

$$X_{s_0} = (e \cos \theta - b \sin \theta) \theta_0 + d \cos \delta - b \sin \delta \dot{\delta} + \dot{S}_0 \quad (11)$$

and $\dot{X}_{s_0}$ =initial horizontal velocity of ship.

Where ship's motion is not constant clearance=missile travel-ship movement,

$$(X - X_0)_{\text{effective}} = \left(\frac{2V_m \cos \theta_0}{-g} \right) [V_m \sin \theta_0 + (e \cos \theta_0 - b \sin \theta_0) \theta_0 + (d \cos \delta_0 - b \sin \delta_0) \dot{\delta}_0 + \dot{S}_0] + \iint_0^{t_f} [(e \cos \theta - b \sin \theta) \dot{\theta} + (d \cos \delta - b \sin \delta) \dot{\delta} + \dot{S}] dt dt \quad (12)$$

where:

$\dot{\theta}$ =roll acceleration

$\dot{\delta}$ =yaw acceleration

$\dot{S}$ =sway acceleration

Where ship motion is not constant flight time would also be modified slightly according to the equation:

$$V_m \cos \theta_0 t f + g/2 t f^2 = \iint_0^{t_f} [e \sin \theta + b \cos \theta] \dot{\theta} + (d \cos \delta - b \sin \delta) \dot{\delta} + \dot{h} dt dt \quad (13)$$

where:

$\ddot{\theta}$ =pitch acceleration

$\ddot{h}$ =heave acceleration

Due to the conditions under which the missile is to be launched, with the ship listed to one side, it may be further assumed that the motions of the ship, after launch, will be toward the vertical and away from the fallback area. Therefore, the missile travel Equations 10 and 11 will have more significance to the SLAG system than 75

will Equations 12 and 13. The missile travel Equations 10 and 11 may, for purposes of simplicity, be reduced to:

$$(X - X_0) = \left(\frac{2V_m \cos \theta_0}{-g} \right) (V_m \sin \theta_0 + e \dot{\theta}_0 \cos \theta_0) \quad (14)$$

Missile travel for a static condition, ignoring motions of the ship, would, therefore, be:

$$(X - X_0) = \frac{V_m^2}{-g} \sin 2\theta_0 \quad (15)$$

This miss distance X must be greater than the distance to the side over which the missile is to be launched plus one-half the missile length in order to allow a safe margin for missile tumble. Some additional clearance may be required due to slewing of the missile and any horizontal motions of the ship should be considered with respect to the distance X to allow a proper safety margin.

To calculate for dynamic conditions, where roll rate is considered and derived from Equations 10 and 11, it would be expressed:

$$(X - X_0) = \frac{V_m^2}{-g} \sin 2\theta + \frac{2V_m}{-g} e \dot{\theta} \cos \theta \quad (16)$$

and

$$Xt = X_0 + X\theta \quad (17)$$

where:

θ =roll or launch angle

$$\dot{\theta} = \theta_0 + \theta \sin \frac{2\pi t}{t}$$

Xt =miss distance with roll rate

The SLAG analog angle computer should be able to predict a safe launch time from the electrical data transmitted by a vertical gyro roll angle control transformer to yield roll angle and roll rate to a prescribed accuracy.

The miss distance of the missile is given by the general Equation (14), neglecting the terms of heave, sway, yaw and pitch:

$$X = \frac{V_m^2}{-g} \sin 2\theta + \frac{2V_m}{-g} e \dot{\theta} \cos \theta - K \quad (18)$$

where, K equals a constant safety factor re-expressed from X_0 .

For any given condition of roll and roll rate, this miss distance may be calculated. However, in launching the missile a value of miss distance must be calculated sometime in the future for allowing time for initiation of missile firing and time for the missile to clear the launcher muzzle.

For the purpose of analysis of the SLAG analog angle computer the motion of the ship will be assumed to be:

$$\theta = \theta_0 + \theta_r \cos \omega t \quad (19)$$

where:

θ_0 =static list angle

θ_r =roll angle

ω =radian roll frequency

t =time

and,

$$\dot{\theta} = -\theta_r \omega \sin \omega t \quad (20)$$

where:

θ =roll rate (angular velocity)

From Equation 10 and 20 it is obvious that:

$$\dot{\theta} = \frac{\theta_{\max.} + \theta_{\min.}}{2} \quad (21)$$

$$\theta_r = \frac{\theta_{\max.} - \theta_{\min.}}{2} \quad (22)$$

$$\omega = \frac{2|\dot{\theta}|_{\max.}}{\theta_{\max.} - \theta_{\min.}} \quad (23)$$

and,

$$w = \frac{\dot{\theta}_{\max.}}{\theta_r} \quad (24)$$

Since the inputs to the system are θ and $\dot{\theta}$, $\theta_{\max}$ is the value of θ when $\dot{\theta}$ swings from positive to negative, and $\theta_{\min}$ is the value of θ when $\dot{\theta}$ swings from negative to positive. Further, therefore, $|\dot{\theta}|_{\max}$ is the value of $|\dot{\theta}|$ when

$$\theta = \frac{\theta_{\max} + \theta_{\min}}{2} \quad (25)$$

when $\dot{\theta}_{\max} = 0$ where, $\theta = \theta_{\min}$ and $\dot{\theta} = \dot{\theta}_{\max}$.

For a missile launching signal at a time ts and a time delay of td (for allowing time to initiate firing and for the missile to clear the launcher muzzle)

$$\theta_L = \frac{\theta_{\max} + \theta_{\min}}{2} + \frac{\theta_{\max} - \theta_{\min}}{2} \cos \left(\frac{2\dot{\theta}_{\max}}{\theta_{\max} - \theta_{\min}} (ts + td) \right) \quad (26)$$

where θ_L = launch angle at time of launch and

$$\theta_L = \theta_{\max} \sin \left(\frac{2\dot{\theta}_{\max}}{\theta_{\max} - \theta_{\min}} (ts + td) \right) \quad (27)$$

where θ_L = launch roll rate plus td .
Therefore,

$$X = \frac{V_m^2}{-g} \sin 2\theta_L + \frac{2V_m}{-g} e 2\dot{\theta}_L \cos \theta_L - K \quad (28)$$

It should, of course, be understood that since the roll and roll-rate conditions are recurrent, they may be re-evaluated after each cycle and the time reset to zero.

The above Equation 28 constitutes the primary elements and terms of the SLAG analog angle computer. Equating once more, however, to illustrate the derivation leading to the final computer equation, the following equation is accumulated from Equations 18 through 27.

$$X = \frac{V_m^2}{-g} \sin 2 \left[\frac{\theta_{\max} + \theta_{\min}}{2} + \frac{\theta_{\max} - \theta_{\min}}{2} \cos \frac{2\dot{\theta}_{\max}}{\theta_{\max} - \theta_{\min}} (ts + td) \right] + \frac{2V_m}{-g} e \dot{\theta}_{\max} \left\{ \sin \left[\frac{2\dot{\theta}_{\max}}{\theta_{\max} - \theta_{\min}} (ts + td) \right] \right\} \left\{ \cos \left[\frac{\theta_{\max} + \theta_{\min}}{2} + \frac{\theta_{\max} - \theta_{\min}}{2} \cos \frac{2\dot{\theta}_{\max}}{\theta_{\max} - \theta_{\min}} (ts + td) \right] \right\} - K \quad (29)$$

For purposes of simplicity in the computer, there is a "GO" condition as an input equation to be solved,

$$A \sin 2\theta_L + B\dot{\theta}_L \cos \theta_L - C > 0 \quad (30)$$

where,

$$A = \frac{V_m^2}{-g}$$

$$\sin 2\theta_L = \sin 2 \left[\frac{\theta_{\max} + \theta_{\min}}{2} + \frac{\theta_{\max} - \theta_{\min}}{2} \cos \frac{2\dot{\theta}_{\max}}{\theta_{\max} - \theta_{\min}} (ts + td) \right]$$

$$B = \frac{2V_m}{-g} e$$

$$\dot{\theta}_L = \theta_{\max} \left\{ \sin \left[\frac{2\dot{\theta}_{\max}}{\theta_{\max} - \theta_{\min}} (ts + td) \right] \right\}$$

$$\cos \theta_L = \left\{ \cos \left[\frac{\theta_{\max} + \theta_{\min}}{2} + \frac{\theta_{\max} - \theta_{\min}}{2} \cos \frac{2\dot{\theta}_{\max}}{\theta_{\max} - \theta_{\min}} (ts + td) \right] \right\}$$

$$C = K$$

From the foregoing it can be seen that the SLAG system contains first, a device to solve Equation 15 for static semi-dynamic conditions and second, an analog

75

angle computer to solve Equation 30 for dynamic conditions.

The SLAG system, as seen in FIGS. 3A, 3B, 3C and 3D, employs two identical systems to provide "fail-safe" operation. That is, through the use of a switching circuit with a dual system of vertical gyros, power supplies, remote indicators, mechanism assemblies, and switching circuits, the selection of either a right system, left system or both systems is permitted. It should, of course, be understood that only a single rather than a dual system may be employed in those instances where this "fail-safe" feature is not considered necessary. Where only a single SLAG system is employed it is apparent that a relay such as relay 130 of FIG. 1 would open and close the firing circuit and a system selector switch would not be needed.

Since both the left and the right systems of the dual SLAG system operate identically only one of the systems will be described in detail without a repetition of an identical description of the remaining system. However, since both systems are illustrated in FIGS. 3A, 3B, 3C, and 3D like reference characters will designate like or corresponding parts throughout except that the system which is not described in detail will employ a prime (').

A vertical gyro 10 is employed in the SLAG system to provide an accurate and dependable vertical reference with respect to the local vertical reference in the form of 400 cycles per second signals. This output from the vertical gyro 10 originates from a synchro pickoff 11 within the gyro 10. The output voltage from stator (14, 15, 16) of pickoff 11 is proportional to the sine of the displacement angle of the gimbals about their axes. The gyro is operated from a 115 volt, three phase, 400 cycles per second power input through lines 20, 21, and 22. This input is applied to gyro 10 through a transformer 23 which is connected across lines 21 and 22 between a power-on switch 24 and rotors (12, 13) of the synchro pickoff 11.

A gravity sensitive vertical reference 30 is employed to provide electrical signals to the torquer motors 31 and 35 across respectively the resistors 32 and 33, and 36 and 37. Maintained across respective inputs to the torquer motors 31 and 35 are compensating for tuning capacitors 34 and 38. Since the electrical output from the vertical reference 30 to the torquer motor 31 is proportional to the ship's pitch and the output to the torquer motor 35 is proportional to the ship's roll, the torquer motor, through the erection transformer 40, controls the gyro motor 41 which maintains and aligns the gyro spin axes to local vertical. Thus, as the gyro motor 41 operates to maintain and align the gyro 10 to the local vertical, displacement of the gyro's gimbals about the pitch and roll axis occurs causing an output from the synchro pickoff 11. The synchro pickoff 11 is oriented so that its output is proportional to the sine of the displacement angle of the gimbals about the roll axis. Of course, it should be understood that a second synchro pickoff could be employed in the same manner as synchro pickoff 11 except that it would be oriented so that its output would be proportional to the sine of the displacement angle of the gimbals about the pitch axis.

A second power input 25 of 115 volts, 60 cycles per second, is applied to a power supply at 26 through a power-on switch 27. Power supply 26 supplies approximately 27 volts D.C. to the various SLAG system components and for accomplishing swift erection of gyro 10 across the output of the power supply 26 is maintained a power-on indicator 28 which by illumination gives a power-on warning.

The duration of time needed for the erection of the gyro 10 through operation of the gyro motor 41 may be shortened through the use of a "fast" erection system. This is accomplished by applying one of the outputs of the torquer motors 31 and 35 directly to the gyro mo-

tor 41 rather than through the erection transformer 40. A manually closable switch 50 applies D.C. from power supply 26 across a solenoid 51 having in parallel therewith a serially connected resistor 52 and diode 53. Thereby a relay 60 is actuated which, as set forth above, switches one of the outputs of the torquer motors 31 and 35 from relay contact 64 to contact 63 causing this output to be fed directly to the gyro motor 41. Also connected in parallel to the solenoid 51 is a heater 54 for actuating a thermostat 55. Upon the closure of relay 60 the thermostat 55 is switched from an open relay contact 62 to contact 61 for applying D.C. to the thermostat which is connected in series with the parallel circuit of the solenoid 51, resistor 52 and diode 53, and heater 54. Thus, D.C. is maintained across the solenoid even after switch 50 is opened and thereby maintains the relay 60 in "fast" erect condition until heater 54 causes thermostat 55 to open the circuit and allow the relay to return to its "normal" erect condition. A fast erection indicator 67 is connected in parallel with a normal erection indicator to respective contacts 65 and 66 of relay 60 across power lines 20 and 21. Thus an illuminated indication is received as to whether the "fast" or the "normal" erection system is in operation.

The gyro 10 having its elements immersed in a viscous fluid employs a temperature control therein for maintaining the temperature and thereby the viscosity of the viscous fluid constant. Connected to the D.C. power supply 26 is a solenoid 71 for actuating a fan 72 connected to a fan brake 73. In parallel across the solenoid 71 is maintained a heater 74 serially connected to a thermostat 75 which applies D.C. to the heater when a decrease in temperature causes the thermostat to close the parallel circuit across the solenoid. Thus the temperature of the viscous fluid is either lowered by the fan 72 or raised by the heater 74.

The signals from the synchro pickoff 11, which are proportional to the ship's roll angle, are fed to a mechanism assembly 80 which is basically a servo loop following up the vertical gyro signals. The input from the synchro pickoff 11 is received by the stator (79, 82, 83) of the control transformer 81 which has an output voltage at the rotor (84, 85) proportional to the sine of the difference between the electrical input angle and the control transformer shaft angle. This output voltage is fed to a servo amplifier 87 through a gain stabilizing resistor 86 which adjusts the gain of amplifier 87 to insure the provision of a stable and sensitive servo loop. The amplifier 87 may, for purposes of example, be a miniaturized transistor amplifier capable of delivering a maximum power output of five watts.

The output voltage of amplifier 87 energizes the control phase of a servo motor 88, which has its tap 89 returning to a D.C. ground potential. A tuning capacitor 90 is employed across the control phase of the servo motor 88 in order to obtain a unity power factor at maximum efficiency while the reference phase of the servo motor is phase shifted 90° from the control phase by a capacitor 91. Capacitor 92 is employed across the reference phase of the servo motor 88 for tuning purposes and for reducing residual voltage.

The servo motor 88, which is a high torque-to-inertia ratio component employs a pinion to drive through a 38:1 gear head 93 and an 11:1 gear pass 94 to mechanically position a main shaft assembly. This main shaft assembly is the pointer shaft of a servo indicator pointer 95 and positions the pointer to provide a visual indication of the ship's list angle. By maintaining slideable "feelers" on the indicator scale the amplitude of ship's roll may be indicated when the pointer 95 engaging the "feelers" swings through the roll angle. The main shaft assembly also positions the rotor (101, 102) of torque transmitter 100, the direction of rotation cam 104 and the roll-angle cam 106. The main shaft assembly also is geared 6:1 at 103 to the

control transformer rotor shaft which is thereby driven through the main shaft assembly by the servo motor 88 until its rotor output voltage equals zero. When the output voltage of the control transformer rotor (84, 95) is zero, the servo loop is nulled with respect to the vertical gyro input signal.

The main shaft assembly also drives through an Oldham coupling and mechanically positions the rotor shaft of the torque transmitter 100. The torque transmitter 100 transmits, to a torque repeater 113 in a remote indicator 112, electrical information corresponding to the angular position of rotor (101, 102) with respect to stator (96, 97, 98). The torque repeater rotor (114, 115) is free to turn and assumes a position with respect to the torque repeater stator (116, 117, 118) in accordance with the electrical information which is received from the torque transmitter 100. Thus, the pointer of the remote indicator 112 is positioned and provides a visual indication of the ship's list angle. Slidable "feelers" may also be employed on a scale of the remote indicator 112. Such "feelers" would be capable of being slidably positioned on the scale by the remote indicator pointer to thereby indicate amplitude of ship's roll. It should, of course, be understood that a plurality of remote indicators may be provided throughout the ship.

A three phase power indicator 18 employs two illuminators connected to respective power lines 20 and 21 and to power line 22 and includes a capacitance 19 for insuring the proper time-phase constant. A power-on illuminator 76 is employed for indicating when the power switch 77 to the torque transmitter rotor (101, 102) has been left open.

A direction of rotation cam 104 is driven through a slip clutch 110 by the main shaft assembly and either opens or closes a micro switch 105. When the ship rolls through its prescribed arc in a starboard direction the main shaft assembly rotates the cam 104 and thereby closes micro switch 105. It should, of course, be understood that the amount of roll required to close micro switch 105 may be adjusted by adjusting cam 104. The ship may then roll one degree or more in the starboard direction and then, because of slip clutch 110, back to port one degree before the micro switch opens. Thus, there is a one degree "dead zone" built into the direction of rotation cam 104. It should, of course, be understood that this "dead zone" may also be increased or decreased by the adjustment of slip clutch 110.

The roll angle cam 106 controls the SLAG system output relay 130 and may be adjusted to any angle desired for safe launching. When a roll-angle is transferred, through the main shaft assembly, to cam 106 the cam rotates and closes micro switch 107 thereby enabling energization of the output relay 130.

Both micro switches, 105 and 107, are connected to one side of the D.C. power supply 26. Serially connected between the micro switch 105 and the other side of the D.C. power supply is a solenoid 120 in parallel with the serially connected resistor 121 and diode 122. Thus, when the starboard roll is satisfactory micro switch 105 closes completing a D.C. circuit thereby energizing the solenoid which is connected to a ganged relay for closing switches 123 and 124. The closure of switch 124 completes a D.C. path across power supply 26 causing illumination of safe starboard roll indicator 125. Closure of micro switch 107, indicating the existence of a safe launch angle, completes another D.C. path thereby illuminating the safe-to-fire indicator 126. Further, with the coincidence of the closures of micro switch 107 and switch 123, which is caused by the closure of micro switch 105, another D.C. path is completed. This D.C. path includes switch 123 and the serially connected parallel circuit of solenoid 131 and resistor 132 and diode 133 which resistor and diode are serially connected. Through the energization of solenoid 131 relay 130 is actuated causing completion of the firing circuit through leads 141

of switch 140. Of course, closure of relay 130 also completes through leads 142 of switch 140 a circuit from the torque transmitters 100 and 100' to remote indicators 112 and 112'. Through leads 142 of switch 140 both remote indicators 112 and 112' will operate to indicate the launch conditions of the ship. The system selector switch 140 selects either the left, right, or both SLAG systems by selecting the left output relay 130, right output relay 130', or both output relays. Since both torque transmitters 100 and 100' of the SLAG systems cannot be employed to drive the remote indicators 112 and 112' only one is connected to the output when switch 140 selects both systems. As can be clearly seen in FIGS. 3A, 3B, 3C, and 3D, contacts 143 of switch 140, which will be connected to the remote indicators through output leads 142 when both systems are selected, are connected only to the torque transmitter 100'.

An analog computer as best seen in FIGS. 6A and 6B may be employed with the SLAG system of FIGS. 3A-3D. The analog computer input is the voltage output of linear transformer 150 which is mounted on the main shaft assembly of the mechanism assembly 80. This output is, therefore, a voltage proportional to the roll angle θ of the ship. Each half of the dual SLAG system employs a separate computer connected to lead 151 and 151'. Where for purposes of economy it is desirable to employ but one computer the output of linear transformers 150 and 150', as best seen in FIG. 5, are connected to one of the ganged switches of selector switch 140. In this manner contact 145 is selected when the right SLAG system operates, or contact 146 is selected when the left SLAG system operates, or contact 144 is selected when both SLAG systems operate. That is, when the right system or both systems are in operation linear transformer 150' will provide the input to the computer but when only the left system is in operation linear transformer 150 will provide the computer input.

The SLAG analog computer, the principal components of which being shown schematically by block diagram in FIGS. 6A and 6B, is employed to solve Equation 30:

$$A \sin Z\theta_L + B\theta_L \cos \theta_L - C > 0$$

where θ is the input angle and varies between plus and minus 30°.

A is a constant of the order of 60 (numerical), B is a constant of the order of 6 (numerical), and C is a constant of the order of 30 (numerical).

The computer is highly reliable since it employs A.C. induction rotating components and static transistor-magnetic amplifiers. Since the input data and solution varies at a relatively slow rate, electro-mechanical A.C. computing may be utilized eliminating the need for less reliable electronic solutions.

Servo positioner module 200 receives its input as a voltage $E\theta$ proportioned to the ship's roll angle θ from a remote, shaft-driven linear transformer 150 mounted on the main shaft assembly in the mechanism assembly 80 of FIGS. 3A-3D. This voltage is converted in module 200 to a shaft angle by being applied through an amplifier 202 to a servo motor 203 after being conditioned at 201 by the feedback voltage from linear transformer 206. The tachometer-generator 204 driven by motor 203 delivers an output voltage $E\theta$ of module 200E proportional to rate-of-change, or $\dot{\theta}$ (roll-rate).

The output of generator 204 of module 200 is fed to a servo motor 223 of module 220 through an amplifier 222 after being conditioned at 221 by the feedback from generator 224 which is driven by servo motor 223. The input voltage is converted by the servo positioner in module 220 to integrated velocity or shaft angle θ_G , which is the original angle θ minus the steady state component θ_0 . Linear transformer 226 on the output shaft is driven through gear box 225 by servo motor 223 and thereby converts this angle to a proportional output voltage $E\theta_G$.

The output of module 200 is also converted to a shaft

angle by servo motor 213 or module 210 after being conditioned at 211 by the feedback voltage from linear transformer 216 and, with the feedback voltage from generator 212, fed through the amplifier 212. The servo motor 213 is stopped at maximum shaft displacement by a gate 217 controlled by relay 218 at negative-going null of $E\theta_G$, the output from linear transformer 226 of module 220.

The maximum shaft displacement is converted to a proportional output voltage $E\theta_m$, maximum roll-rate, by the linear transformer 216 which is driven on the output shaft by servo motor 213 through gear box 215.

The output of module 220, $E\theta_G$, is converted in the position servo of module 230 by applying this voltage to servo motor 233 after being conditioned at 231 by the feedback voltage from linear transformer 236 and, with the feedback from generator 234, fed through amplifier 232. However, the servo motor 233 is stopped at maximum shaft displacement by a gate 237 controlled by relay 238 at the negative-going null of roll-rate voltage $E\dot{\theta}$ which is the output from linear transformer 206 of module 200. The maximum shaft displacement is converted to a proportional output voltage $E\theta_r$, roll-amplitude, by the linear transformer 236 which is driven on the output shaft by servo motor 233 through gear box 235.

Voltage $E\theta_G$ from the linear transformer 226 of module 220 is also fed through amplifier 242 to the servo motor 243 driving through gear box 245 of module 240 after being nulled against the output fed back from a driven resolver 246. Thus, a shaft angle is obtained which is equal to

$$wts = \frac{E\theta_G}{E\theta_r}$$

35 $E\theta_r$ is then converted to an output voltage vector $Ewts$ by a driven synchro transmitter 247. Derived from the generator 245 which is driven by motor 243 in an output voltage EW which is proportional to roll frequency W .

The output voltage EW from generator 244 of module 40 240 is attenuated by potentiometer 258 connected to ground potential to obtain a voltage proportional to the product Wtd . This voltage $Ewtd$ is fed to servo motor 253 of module 250 after being conditioned at 251 by the feedback from linear transformer 256 and, with the feedback from generator 254, fed through amplifier 252 to thereby obtain a shaft angle Wtd . This shaft angle positions through a gear box 255 a synchro differential transmitter 257 in series with the wts synchro transmitter 247 of module 240 to obtain an output voltage vector

$$EW(ts+td)$$

for angle $W(ts+td)$.

The output of the differential transmitter 257 is fed to the control transformer 267 and then to servo motor 262, driving through gear box 264 of module 260, with a feedback from generator 263 through the amplifier 261 to obtain a shaft angle proportional to $W(ts+td)$. The shaft positions two resolvers 265 and 266 which are excited respectively by output voltages $E\theta_r$ of module 230 and $E\theta_m$ of module 210. The outputs of the resolvers 265 and 266 are then proportional respectively to:

$$\theta_m \cos w(ts+td)$$

and

$$\theta_m \sin w(ts+td) - \theta_L$$

65 The output from linear transformer 266 of module 260 is subtracted from subtractor 266 from the output of linear transformer 206 of module 200 to obtain a voltage $E\theta_0$ proportional to steady-state displacement. This voltage is then added by adder 269 to the output of roll resolver 265 of module 260 to obtain voltage $E\theta_L$ proportional to $\theta_r \cos w(ts+td) + \theta_0 = \theta_L$, the predicted launch angle. Position servo of module 270 applies the input voltage $E\theta_L$ to servo motor 273 for driving through gear box 275 after it is conditioned at 271 by a feedback from linear transformer 276 and, with the feedback from gen-

erator 274, fed through amplifier 272. Thereby input voltage $E\theta_L$ is then converted to a shaft angle θ_L and the output of the linear transformer 276 on the shaft is a voltage $E\theta_L$ proportional to θ_L which may be read on a panel meter 279 and connected to other remote indicators through lead 192. The input $EB\theta_L$ to resolver 277 is obtained from the output of an adjustable-gain amplifier 281. Amplifier 281 is fed a voltage $E\theta_L$ from resolver 266 of module 260 after being conditioned at 280 by a tap from potentiometer 282 which is connected between the output of amplifier 281 and ground potential. The output of resolver 277 of module 270 is then $EB\theta_L \cos \theta_L$. The input EA to resolver 278 of module 270 is obtained from a manually adjusted potentiometer 283 connected to ground potential. The output of resolver 278 is then $A \sin Z\theta_L$. Of course, to obtain these outputs from resolvers 277 and 278, resolver 277 must be capable of being positioned on the servo shaft at one speed and resolver 278 at two speeds. The outputs of resolvers 277 and 278 are then added to adder 284 to obtain

$$EA \sin Z\theta_L + B\theta_L \cos \theta_L$$

From this sum is subtracted the output voltage from manually adjustable potentiometer 285 which is connected to ground potential. This output voltage from potentiometer 285 is proportional to the quantity 'C' thereby obtaining Equation 30.

$$A \sin Z\theta_L + B\theta_L \cos \theta_L - C > 0$$

This final resultant is then applied to a phase sensitive detector 288 through amplifier 287 to detect for Equation 30. Detection of Equation 30 causes actuation of relay 289 and thereby illuminating the "GO" light 190 and extinguishing the "NO-GO" light 191.

The output voltage Ew from generator 244 of module 240 which is proportional to roll frequency w , is converted to shaft velocity by the velocity servo of module 300. The servo motor 303 drives through the gear box 305 in response to the input voltage which is conditioned by feed back of generator 304 and fed through an amplifier 302. An electro-magnetic clutch 306 on the shaft of this servo motor engages, in response to the "GO" condition output from relay 289, a linear transformer 308 during the "GO" period, to integrate wT_G where T_G is "GO" duration. Since $T_G/T_p = T_G/1/w = wT_G$ where T_p is period and w is roll frequency, percent of "GO" time is proportional to the output voltage from linear transformer 307 of module 300. This voltage may be read by a panel meter 308 as percentage "GO" time and may also be connected to a plurality of other remote indicators through lead 309. Of course, a spring will be employed to return the linear transformer 307 to zero at the end of each "GO" period.

A self-check switch 310 is provided at the input of the analog computer so as to provide the capability of checking the operation of the analog computer with a reference voltage to insure proper operation of the computer before actual operation is attempted.

Obviously, many modifications and variations of the present invention are possible in light of the above teachings. It is, therefore, to be understood that within the scope of the appended claims the invention may be practiced otherwise than is specifically described.

What is claimed and desired to be secured by Letters Patent of United States is:

1. A safe launch angle gate system for preventing missile launching from a marine vessel when missile fallback would damage said vessel and for allowing firing when safe fallback conditions exist comprising; a vertical gyro for sensing angular movement of said vessel about its longitudinal axis and having an output voltage proportional to the sine of said movement about said axis, switch means, actuating means electrically connected to said switch means and responsive to said vertical gyro output for indicating said vessel's motion and for actu-

ating said switch means when said vessel has achieved an angular relationship about its longitudinal axis with respect to the vertical to avoid missile fallback damage, said actuating means comprising; a main shaft assembly for operating said switch means, amplifier means, servo motor means for driving said main shaft assembly, and a control transformer connected through said amplifier means to said servo motor means; and relay means connected to said switch means for completing a missile firing circuit.

5 2. A safe launch angle gate as claimed in claim 1 wherein said switch means comprises a first cam member on said main shaft assembly and a first switch connected thereto for actuating a first relay of said relay means, and a second cam member on said main shaft assembly and a second switch for actuating a second relay of said relay means.

15 3. A safe launch angle gate system as claimed in claim 2 wherein said first cam member is connected to said main shaft assembly through a slip clutch for allowing, after said first switch closes, at least one degree angular movement in a safe direction and one degree back in an unsafe direction before said first switch reopens.

20 4. A safe launch angle gate system as claimed in claim 3 wherein said first relay comprises a resistor and a diode interconnected in series and a solenoid connected in parallel with said resistor and diode for closing a third and a fourth switch.

25 5. A safe launch angle gate system as claimed in claim 4 wherein said third switch is connected in series with said second relay and wherein said second relay comprises a resistor and a diode interconnected in series and a solenoid connected in parallel with said resistor and diode for closing a firing circuit.

30 6. A safe launch angle gate system as claimed in claim 5 wherein said main shaft assembly comprises a gearing means for controlling the rotor shaft of said control transformer whereby the output of said control transformer is proportional to the sine of the difference between the electrical input angle and the shaft angle of said control transformer.

35 7. A safe launch angle gate system as claimed in claim 6 wherein said amplifier means comprises a servo transistor amplifier and a stabilizing resistor connected between the output of said control transformer and the input to said amplifier for adjusting amplifier gain.

40 8. A safe launch angle gate system as claimed in claim 7 wherein said servo motor means comprises a high torque-to-inertia servo motor and a first tuning capacitor connected across the control phase of said servo motor for achieving a unity power factor at maximum efficiency.

45 9. A safe launch angle gate system as claimed in claim 5 wherein said means responsive to said vertical gyro output for indicating said vessel's motion comprises a torque transmitter having a rotor connected to the reference phase of said servo motor, a torque repeater having a stator connected to the stator of said torque transmitter for indicating said angular motions of said vessel by rotation of the torque repeater rotor with respect to said torque repeater stator, and a second capacitor connected across the reference phase of said servo motor for tuning and for reducing residual voltage.

50 10. A dual safe launch angle gate system for preventing missile launching from a marine vessel when missile fallback would damage said vessel and for allowing firing when safe fallback conditions exist comprising; a first safe launch angle gate system having a first vertical gyro for sensing angular movement of said vessel about the longitudinal axis thereof and having an output voltage proportional to the sine of said movement about said axis, first switch means, first actuating means responsive to said first vertical gyro output for indicating said vessel's angular motion and for actuating said first switch means when said vessel has achieved an angular relationship about its longitudinal axis with respect to the vertical to thereby avoid missile fallback damage, said first actuating means

comprising; a first main shaft assembly for operating said first switch means, first amplifier means, first servo motor means for driving said first main shaft assembly, and a first control transformer connected through said first amplifier means to said first servo motor; and first relay means connected to said first switch means; a second safe launch angle gate system having a second vertical gyro for sensing angular movement of said vessel about said longitudinal axis and having output voltage proportional to the sine of said movement about said axis, second actuating means responsive to said second vertical gyro output for indicating said vessel's motion and for actuating said second switch means when said vessel has achieved an angular relationship about its longitudinal axis with respect to the vertical to thereby avoid missile fallback damage, said second actuating means comprising a second main shaft assembly for operating said second switch means, a second amplifier means, a second servo motor means for driving said second main shaft assembly, and a second control transformer connected through said second amplifier means to said second servo motor; second relay means connected to said second switch means; and a system selector switch having first contacts for selecting said first safe launch angle gate system and having second contacts for selecting said second safe launch angle gate system for closing a firing circuit while both said first and second safe launch angle gate systems are available to determine the presence of a safe launch angle should the other system fail.

11. A dual safe launch angle gate system as claimed in claim 10 wherein said system selector switch has a third set of contacts whereby both said first and second safe launch angle gate systems can operate simultaneously to close said firing circuit.

12. A dual safe launch angle gate system as claimed in claim 10 wherein said first switch means comprises a first cam member on said first main shaft assembly and a first switch connected thereto for actuating a first relay of said first relay means, and a second cam member on said first main shaft assembly and a second switch connected thereto for actuating a second relay of said first relay means; and wherein said second switch means comprises a third cam member on said second main shaft assembly and a third switch connected thereto for actuating a third relay of said second relay means, and a fourth cam member on said second main shaft assembly and a fourth switch connected thereto for actuating a fourth relay of said second relay means.

13. A dual safe launch angle gate system as claimed in claim 12 wherein said first and third cam members are connected respectively to their first and second main shaft assemblies through respective first and second slip clutches for allowing, after said first and third switches close, at least one degree angular movement in a safe direction and one degree back in an unsafe direction before said respective first and third switches reopen.

14. A dual safe launch angle gate system as claimed in claim 13 wherein said first relay of said first relay means comprises a resistor and a diode interconnected in series and a solenoid connected in parallel with said resistor and diode for closing a fifth switch and a sixth switch and wherein said third relay of said second relay means comprises a resistor and a diode interconnected in series and a solenoid connected in parallel with said resistor and diode for closing a seventh and an eighth switch.

15. A dual safe launch angle gate system as claimed in claim 14 wherein said fifth switch is connected in series with said second relay of said first relay means and wherein in said second relay of said first relay means comprises a resistor and a diode interconnected in series and a solenoid connected in parallel with said resistor and diode; and further wherein said seventh switch is connected in series with said fourth relay of said second relay means and wherein said fourth relay comprises a resistor and a diode interconnected in series and a solenoid connected

in parallel with said resistor and diode whereby said second relay of said first relay means connects said first safe launch angle gate system to said system selector switch and said fourth relay connects said second safe launch angle gate system to said system selector switch for closing a firing circuit.

16. A dual safe launch angle gate system as claimed in claim 15 wherein said first main shaft assembly comprises a first gearing means for controlling the rotor shaft of said first control transformer and wherein said second main shaft assembly comprises a second gearing means for controlling the rotor shaft of said second control transformer whereby the outputs of said first and second control transformers are proportional to the sine of the difference between the electrical input angles thereto and the shaft angles of said first and second control transformers.

17. A dual safe launch angle gate system as claimed in claim 16 wherein said first amplifier means comprises a first servo transistor amplifier and a first stabilizing resistor connected between the output of said first control transformer and the input to said first amplifier for adjusting the amplifier gain, and wherein said second amplifier means comprises a second servo transistor amplifier and a second stabilizing resistor connected between the output of said second control transformer and the input to said second amplifier for adjusting amplifier gain.

18. A dual safe launch angle gate system as claimed in claim 17 wherein said first servo motor means comprises a first high torque-to-inertia servo motor and a first tuning capacitor connected across the control phase of said first servo motor for achieving a unity power factor at maximum efficiency, and wherein said second servo motor means comprises a second high torque-to-inertia servo motor and a second tuning capacitor across the control phase of said second servo motor for achieving a unity power factor at maximum efficiency.

19. A dual safe launch angle gate system as claimed in claim 15 wherein said first means responsive to said first vertical gyro output for indicating said vessel's motion comprises a first torque transmitter having the rotor thereof connected to the reference phase of said first servo motor and having its stator electrically connected to said first system selector switch contacts, a first and a second torque repeater having the stators thereof connected to said system selector switch for indicating said angular motions of said vessel by rotation of said first and second torque repeater rotors with respect to the stators thereof; further wherein said second means responsive to said second vertical gyro output for indicating said vessel's motion comprises a second torque transmitter having the rotor thereof connected to the reference phase of said second servo motor having its stator electrically connected to said second system selector switch contact; and further wherein said third set of contacts of said system selector switch are electrically connected to said first system selector switch contacts whereby said first torque transmitter is electrically connected through said system selector switch to said first and second torque repeaters when said first safe launch angle gate system is in operation and when both said first and second safe launch angle gate systems are in operation and whereby said second torque transmitter is electrically connected to said first and second torque repeaters when said second safe launch angle gate system is in operation.

20. An analog computer for computing future longitudinal angles for marine vessels comprising; an input proportional to said vessel's roll angle, first computing means responsive to said input for converting said input to a voltage signal proportional to said vessel's roll-rate, second computing means electrically connected to said first computing means for converging said roll-rate signal to a voltage signal proportional to said vessel's integrated roll velocity, third computing means electrically connected to said first computing means for converting said roll-rate signal to a voltage signal proportional to said ship's maxi-

mum roll-rate, fourth computing means electrically connected to said second computing means for converting said integrated roll velocity signal to a voltage signal proportional to said ship's roll amplitude, fifth computing means electrically connected to said second computing means for converting said integrated roll velocity signal to a first voltage signal proportional to the vessel's roll frequency at the time of missile firing and a second voltage signal proportional to the missile roll frequency, means electrically connected to said fifth computing means for attenuating said second output voltage signal of said fifth computing means to induce a delay time, sixth computing means electrically connected to said attenuating means and being responsive to said attenuated signal and to said first output voltage signal of said fifth computing means for converting said signals to an output voltage signal proportional to roll frequency at a time in excess of missile firing time, means for subtracting said first computing means output voltage signal proportional to roll-rate and said second computing means output voltage signal proportional to integrated roll velocity for thereby obtaining a voltage signal proportional to steady-state displacement, seventh computing means electrically connected to and responsive to said sixth computing means output voltage signal, said seventh computing means having a first resolver means electrically connected to and responsive to said roll amplitude voltage signal for thereby deriving an output, which, when added to said voltage signal proportional to steady-state displacement, is proportional to a future launch angle, said seventh computing means also having a second resolver means electrically connected to and responsive to said maximum roll-rate voltage signal for thereby deriving an output voltage signal proportional to said vessel's roll-rate at said future launch angle, an adder, eighth computing means electrically connected and responsive to said voltage signal proportional to said future launch angle and having an output proportional to said predicted launch angle, and said eighth computing means further having third and fourth resolvers having the outputs thereof connected to said adder, first potentiometer means for introducing a first constant voltage to said third resolver, second potentiometer means connected to said second resolver output for introducing therewith a constant voltage to said fourth resolver and a third potentiometer means connected to the output of said adder for subtracting a constant voltage from said computer and thereby predicting the angle of said marine vessel with respect to said vertical plane through said longitudinal axis at a future time approximately equivalent to the time required to initiate missile firing and for said missile to clear the launcher muzzle.

21. An analog computer for computing future launching angles from a marine vessel such as that claimed in claim 20 including; first indicator means connected to said computing means for indicating said vessel's roll angle, second indicator means connected to said computing means for indicating the percentage of firing time remaining in a safe firing period, means connected to said computing means for detecting a prescribed future angular relationship for safe firing conditions free of fallback hazards, third indicator means, and means connected to said detector means and said third indicator means for conditioning said second and third indicators in response to safe conditions detected by said detection means thereby indicating the presence of said safe conditions whereby launching may be initiated causing missile exit from a launcher muzzle when said vessel is at a safe launching angle with respect to said vertical plane.

22. An analog computer as claimed in claim 21 wherein said first indicator means is electrically connected to said eighth computing means output which is proportional to said future launch angle whereby said vessel's roll angle may be visually indicated.

23. An analog computer as claimed in claim 22 wherein said second indicator means comprises a ninth comput-

ing means electrically connected and responsive to said fifth computing means, second output signal proportional to said vessel's roll frequency and having means responsive to said activating means during safe launch periods for deriving to indicators an output signal proportional to the percentage of safe launch time remaining in a safe launch period.

24. An analog computer as claimed in claim 23 wherein said conditioning means comprises a relay and wherein said third indicator means comprises safe and unsafe illuminators connected to said relay.

25. A safe launch angle gate system for preventing missile launching from a marine vessel when missile fallback would damage said vessel and for allowing firing when safe fallback conditions exist comprising; a vertical gyro for sensing angular movement of said vessel about its longitudinal axis and having an output voltage proportional to the sine of said movement about said axis, switch means, actuating means responsive to said vertical gyro output for indicating said vessel's motions and for actuating said switching means when said vessel has achieved an angular relationship about said longitudinal axis with respect to said vertical plane to avoid missile fallback damage, said actuating means comprising; a main shaft assembly for operating said switching means, a linear transformer mounted on said main shaft assembly having an output proportional to said vessel's roll angle for providing an input to said computer, an amplifier means, a servo motor means for driving said main shaft assembly, and a control transformer connected through said amplifier means to said servo motor means; relay means connected to said switch means for completing a fire circuit, and an analog computer for predicting future launch angles and indicating the future existence of safe launch angles.

26. A safe launch angle gate system as claimed in claim 25 wherein said computer comprises an input means responsive to said input from said linear transformer proportional to said vessel's roll angle for computing future angular relationships of said marine vessel during rotation about the longitudinal axis thereof with respect to a vertical plane parallel to said longitudinal axis, first indicator means connected to said computing means for indicating said ship's roll angle, second indicator means connected to said computing means for indicating percentage of firing time remaining in a safe firing period, means connected to said computing means for detecting a prescribed future angular relationship having safe firing conditions free of fallback hazards, third indicator means, and means connected to said detector means and said second and third indicator means for conditioning said second and third indicators in response to detection of safe conditions by said detection means thereby indicating the presence of said safe conditions by said indicators whereby launching may be initiated causing missile exit from a launcher muzzle when said vessel is at a safe launching angle with respect to said vertical plane.

27. A safe launch angle gate system as claimed in claim 26 wherein said switch means comprises a first cam member on said main shaft assembly and a first switch connected thereto for activating a first relay of said relay means, and a second cam member on said main shaft assembly and a second switch for actuating a second relay of said relay means.

28. A safe launch angle gate system as claimed in claim 27 wherein said first cam member is connected to said main shaft assembly through a slip clutch for allowing, after said first switch closes, at least one degree angular movement in a safe direction and one degree back in an unsafe direction before said first switch reopens.

29. A dual safe launch angle gate system for preventing missile launching from a marine vessel when missile fallback would damage said missile and for allowing firing when safe fallback conditions exist comprising; a first safe launch angle system having a first vertical gyro for sensing angular movement of said vessel about the longi-

tudinal axis thereof and having an output voltage proportional to the sine of said movement about said axis, first switching means, first actuating means responsive to said first vertical gyro output for indicating said vessel's motions and for actuating said first switching means when said vessel has achieved an angular relationship about said longitudinal axis with respect to the vertical to thereby avoid missile fallback damage, and first relay means connected to said first switching means; a second safe launch angle gate system having a second vertical gyro for sensing angular movement of said vessel about said longitudinal axis and having an output voltage proportional to the sine of said movement about said axis, second switching means, second actuating means responsive to said vertical gyro output for indicating said vessel's motions and for actuating said second switching means when said vessel has achieved an angular relationship about said longitudinal axis with respect to the vertical to thereby avoid missile fallback damage, and second relay means connected to said second switching means; said first and second actuating means comprising respectively first and second main shaft assemblies for operating said first and second switching means, a first and second linear transformer mounted to first and second main shaft assemblies having an output proportional to said vessel's roll angle for providing an input to said computing means, a first and second amplifier means, a first and second servo motor means for respectively driving said first and second main shaft assemblies, and a first and second control transformer connected through said respective first and second amplifier means to said first and second servo motor means; a system selector switch having first contact for selecting said first safe launch angle gate system and having second contact for selecting said second safe launching angle gate system for closing a firing circuit; and means connected to said dual safe launching angle gate system for computing future launch angles and for indicating future existence of safe launching angles.

30. A dual safe launch angle gate system as claimed in claim 29 wherein said computer means comprises an input from said first linear transformer, first means for computing a future angular relationships of said marine vessel during rotation about the longitudinal axis thereof with respect to a vertical plane parallel to said longitudinal axis, first indicator means connected to said first computing means for computing said vessel's roll angle, second indicator means connected to said first computing means for indicating the percentage of firing time remaining in a safe firing period, first means connected to said first computer means for detecting a prescribed future angular relationship having safe firing conditions free of fallback hazards, third indicator means, and first activating means connected to said first detector means and said second and third indicator means for activating said second and indicator means in response to detection of safe conditions by said detecting means thereby indicating the presence of safe launch conditions; and wherein in said computer means further comprises an input from

said second linear transformer, second means for computing future angular relationships of said marine vessel rotating about said longitudinal axis with respect to said vertical plane parallel to said longitudinal axis, fourth indicator means connected to said computing means for indicating said vessel's roll angle, fifth indicator means connected to said computing means for indicating percentage of firing time remaining in a safe firing period, second means connected to said second computing means for detecting a prescribed future angular relationship having safe firing conditions free of fallback hazards, sixth indicator means, and activating means connected to said second detector means and said fifth and sixth indicator means for activating said fifth and sixth indicator means in response to detection of safe conditions by said second detecting means thereby indicating the presence of safe conditions on said indicators whereby launching may be initiated causing missile exit from a launcher muzzle when said vessel is at a safe launching angle with respect to said vertical plane.

31. A dual safe launch angle gate system as claimed in claim 29 wherein said outputs of said first and second linear transformers are electrically connected to said system selector switch for electrically connecting the output of said first linear transformer to said computer means when said first safe launch angle gate system is in operation and when both said first and second safe launch angle gate systems are in operation, and for electrically connecting the output of said second linear transformer to said computer means when only said second safe launch angle gate system is in operation.

32. A dual safe launch angle gate system as claimed in claim 31 wherein said computer means comprises an input proportional to said vessel's roll, means for computing future relationships of said marine vessel during rotation about said longitudinal axis with respect to said vertical plane, first indicator means connected to said computing means for indicating said vessel's roll-angle, second indicator means connected to said computing means for indicating percentage of safe firing time remaining in a safe firing period, means connected to said computing means for detecting a prescribed future angular relationship having safe firing conditions free of fallback hazards, third indicator means, and actuating means connected to said detector means and said second and third indicator means for activating said second and third indicator means in response to detection of safe conditions by said detection means thereby indicating the presence of said safe conditions whereby launching may be initiated to cause a missile exit from a launcher muzzle when said vessel is at a safe launching angle with respect to said vertical plane.
